UNITED STATES PATENT OFFICE

JAMES MCKEAGUE, OF CHICAGO, ILLINOIS, ASSIGNOR, BY MESNE ASSIGNMENTS, TO
ZEROZONE, INCORPORATED, OF CHICAGO, ILLINOIS, A CORPORATION OF DELAWARE

EVAPORATOR

Application filed March 3, 1930. Serial No. 433,930.

This invention relates to improvements in boilers and has for its principal object the production of a new and improved boiler or cooling unit for a mechanical refrigerating system.

In mechanical refrigerating systems the cooling unit disposed in the refrigerator to be cooled by the system usually comprises a horizontal drum out of the bottom of which are led a plurality of circulating coils through which heat in the box is drawn into the refrigerant in the unit. A compressor unit is employed to withdraw the vapor formed by the boiling of the refrigerant in the cooling unit from that unit and to compress it and circulate it through a cooling medium to convert it into liquid, which is then returned to the cooling unit by the compressor.

In a system of this kind the horizontal drum or boiler is maintained partially full of liquid refrigerant by a float controlled valve governing the admission of liquid into the unit. Frequently the compressor employed to withdraw the gas from the unit is adapted to withdraw the gas from a number of cooling units in what is known as a centralized system. In other cases the compressor is individual through the cooling unit in the so-called individual unit system.

In both of these systems, oil used to lubricate the piston and cylinder walls of the compressor finds its way into the liquid refrigerant and is emulsified with that liquid and returned to the cooling unit therewith. In the cooling unit the oil and refrigerant separate and since the oil is lighter than the refrigerant it collects as a film upon the surface of the liquid. This oil forms a blanket over the surface of the liquid and the presence of this blanket retards the evaporation of the refrigerant and consequently the withdrawal of heat from the refrigerator is thereby diminished.

If no arrangements are made for withdrawing the film of oil from the surface of the refrigerant in the cooling unit, that unit will soon become oil bound because the film of oil will be so thick that it will be practically impossible to draw the vaporized refrigerant through it and from the unit. To

overcome this condition, various devices, of which I am aware, have heretofore been employed to skim the film of oil from the surface of the refrigerant and to return it to the compressor with the gas withdrawn from the unit.

An arrangement of this kind is satisfactory only as long as it is capable of withdrawing oil from the unit without picking up any liquid refrigerant. If liquid refrigerant is picked up, that refrigerant is vaporized in the pipes leading to the compressor with the result that the temperature of those pipes is reduced below the dew point and moisture in the air is collected on them in the form of dew or frost. When the compressor is shut down this frost melts and drops of water are formed on the pipes by the melting frost and fall from it to injure the walls of the building, in the case of a centralized unit system, or the walls of the refrigerator in the case of an individual unit system.

In the arrangements provided heretofore this withdrawing of liquid refrigerant has frequently happened because the agitation of the refrigerant in the drum particularly when the box is relatively warm and the boiling or vaporization of the refrigerant is therefore rapid. The surface of the oil is agitated by the passing of gas from the liquid refrigerant in the space above it and this agitation frequently brings the liquid refrigerant into engagement with the skimming device with the result that the liquid is picked up and drawn into the suction system.

In my present invention I have provided an arrangement for producing a zone of quiet adjacent the skimming device so that even when the refrigerant is boiling violently the skimmer will not pick up liquid refrigerant but will pick up the oil film from the surface of that liquid.

Now to acquaint those skilled in the art with the teachings of my invention, reference is made to the accompanying drawing in which a preferred embodiment of it is shown by way of example and in which:

Figure 1 is a cross sectional view taken longitudinally through a boiler;

Figure 2 is an end view of the boiler;

Figure 3 is a cross sectional view taken along the line 3 of Figure 1; and

Figure 4 is a perspective view of the suction pipe and baffle.

Referring to the drawing in more detail, the boiler comprises the cylindrical drum 1 which is rolled into groove 2 in the ring 3 and soldered to form a pressure tight joint between the drum and ring. Usually the drum 1 is constructed of seamless brass tubing and the ring 3 is a brass forging, although any other preferred materials may be substituted therefor. The drum is closed by a cover plate 4 which is bolted to the ring 3 by bolts 5 to form a pressure tight joint.

The cover 4 carries the suction port and valve 6 and the pressure port and valve 7, which valves may be varied within the teachings of my invention. The suction line, not shown, is connected to the suction valve 6 and the pressure line to the pressure valve 7, these lines leading to a compressor unit, not shown, to permit it to operate the cooling unit in the usual manner.

In Figure 2 the pressure valve 7 is shown in cross section and comprises the pressure line 8 leading from the compressor to the valve seat member 9 through which it is attached by the union 10. The valve seat member 9 opens into a chamber 11 which communicates with the inside of the drum through the port 12. A valve 13 is threaded into the walls of this chamber 11 at the opposite end by the thread 14 and operable thereon to engage the valve seat 9 to close the chamber 11 from the pipe 8. The valve 13 is operated by the square shank 15 which is normally encased by a cap nut 16, that cap nut being removable when it is necessary to close the valve.

Within the drum 1 is a needle valve 17 which is operated by float 18 to open or close the port 12 leading into the drum. The float 18 controls the valve 17 to regulate the height of the liquid 19 in the drum.

The liquid refrigerant 19 is covered with a film of oil 20, that film being the oil that it is desired to skim from the unit.

The suction valve 6 leads through a port 21 to the suction pipe 22 which comprises a horizontal portion 23 and a curved portion 24 leading to the open end 25 which is disposed near the top of the drum 1. An oil skimming port 26 is disposed in the horizontal portion 23 of suction pipe 22 and when the float 18 is properly adjusted the liquid level in the drum is maintained at such a height that the port 26 is disposed in the upper part of the film of oil 20.

A baffle 30 is attached to the horizontal portion 23 of the suction pipe and comprises a planar portion 31 extending horizontally out from the suction pipe just below the skimming port 26. The baffle also comprises vertical members 32 and 33 located on opposite

ends of the horizontal portion 31 and on opposite sides of the skimming port 26. Preferably the baffle 32 adjacent the end plate 4 of the drum is higher than the other vertical baffle 33, extending well above the horizontal portion 23 of the suction pipe.

As will be noted in Figure 3, the suction pipe 22 is located to one side of the vertical center line of the drum 1, and the needle valve 17 and float 18 are located centrally in the drum. The baffle 30 extends from the suction pipe 22 toward and beyond the center line of the drum so that it is disposed directly above a needle valve 17.

In operation, the escape of vaporized refrigerant, or so called boiling of the refrigerant in the drum, takes place most violently immediately above the opening leading from the circulating coils into the drum. In devices of this kind now generally on the market these openings are located near the bottom of the drum and on opposite sides of the center line of it so that the gas rising through the liquid refrigerant follows a path near the outside of the drum. The particular location of the points of entry of the cooling coils into the drum may be varied within the teachings of my invention and for that reason no particular form has been shown in the drawing.

The agitation of the liquid refrigerant caused by this movement of gas through it is prevented from disturbing the oil film adjacent the skimming port 26 by the horizontal portion 23 of the suction pipe 22 and by the horizontal portion 31 of the baffle extending from that pipe on the side containing the skimming port. Since the horizontal baffle extends well beyond the center line of the drum, it is effective to maintain a relatively large quiet area adjacent the skimming port 26. The upturned end 33 of the baffle aids in maintaining this zone of quiet.

Some boiling also occurs around the needle valve due to the movement of liquid refrigerant from the high pressure line 8 to the lower pressure interior chamber of the drum 1, the gas so formed rising vertically from the needle valve is prevented from disturbing the oil film in the skimming area by the high vertical portion 32 of the baffle. Violent boiling in the end of the drum away from the head 4 is prevented from disturbing the skimming area by the float 18 with the assistance of the vertical portion 33 of the baffle. The liquid in the skimming area above the horizontal portion 31 of the baffle moves with unidirectional motion through the open end of the area and toward the skimming port 26. This motion is slow because the cross sectional area of the port 26 is relatively small in comparison to the cross sectional area of the skimming area, and as a result the oil is completely separated from the refrigerant and collected upon the top thereof. I have

found that this arrangement produces a zone sufficiently quiet to permit skimming oil from the refrigerant without picking up any liquid refrigerant even when the liquid in the drum is boiling violently.

Having thus complied with the statutes and shown and described a preferred embodiment of my invention, what I consider new and desire to have protected by letter of patent is pointed out in the attendant claims.

What is claimed is:

1. In a mechanical refrigerator, a boiler, a liquid refrigerant therein, means for maintaining said liquid at a predetermined level in the boiler, said liquid being vaporized and the gas so formed permitted to rise to the top of the boiler, there being a film of oil on the surface of said liquid which is agitated by the bubbles of gas passing through it, a suction pipe extending into said drum to withdraw the gas from it and having an oil skimming port imbedded in said film, and means including a baffle supported on said pipe comprising a portion extending horizontally from said pipe below said port and vertical portions disposed on opposite sides of said port, said baffle defining a shallow basin closed on one end by said suction pipe for preventing agitation of said film adjacent said port to prevent drawing liquid refrigerant through said port with said oil.

2. In a mechanical refrigerating unit, the combination with a boiler drum in which a liquid refrigerant is maintained at a certain height by a float controlled valve, a suction pipe in said drum which is partly submerged in said liquid and contains a port in its submerged portion just below the surface of said liquid, of a baffle including a horizontal portion located beneath said port and attached to said pipe and vertical portions disposed on opposite sides of said port attached to said pipe, one of said vertical portions extending above the pipe to shield said port from liquid rising from said valve.

3. In a mechanical refrigerating unit, the combination with a boiler drum in which a liquid refrigerant is maintained at a certain height by a float controlled valve, of a suction pipe in said drum which is partly submerged in said liquid and contains a skimming port in its submerged portion just below the surface of said liquid, a baffle attached to said pipe and including a horizontal portion located beneath said port and vertical portions disposed on opposite sides of said port, said baffle forming a basin which is closed at the bottom and on two sides by said baffle and on one end by said pipe, said liquid filling said basin to permit its being skimmed through said port.

4. In a mechanical refrigerating unit, the combination with a boiler drum in which a liquid refrigerant is maintained at a certain height by a float controlled valve, of a suc-

tion pipe in said drum which is located to one side of the center thereof and is partly submerged in said liquid, said pipe containing a skimming port located in said submerged portion and opening toward the center of said drum, a baffle attached to said submerged portion of said pipe and extending horizontally therefrom beyond the center of said drum, vertical side pieces on said baffle extending upwardly therefrom, said baffle forming a basin closed at one end by said pipe and on opposite sides by said side pieces, said liquid moving into said basin through the open end thereof with unidirectional movement to permit it being skimmed through said port.

In witness whereof, I hereunto subscribe my name this 25 day of Feb., 1930.

JAMES McKEAGUE.
